US00D983879S

(12) **United States Design Patent** (10) **Patent No.:** **US D983,879 S**
Hyun et al. (45) **Date of Patent:** **** Apr. 18, 2023**

(54) **ELECTRONIC BLACKBOARD**

(71) Applicant: **LG ELECTRONICS INC.**, Seoul (KR)
(72) Inventors: **Joe Hyun**, Seoul (KR); **Seungdon Lee**, Seoul (KR); **Sangwon Yoon**, Seoul (KR)
(73) Assignee: **LG ELECTRONICS INC.**, Seoul (KR)
(**) Term: **15 Years**
(21) Appl. No.: **35/513,048**
(22) Filed: **May 28, 2021**
(80) **Hague Agreement Data**

Int. Filing Date: **May 28, 2021**

Int. Reg. No.: **DM/214606**

Int. Reg. Date: **May 28, 2021**

Int. Reg. Pub. Date: **Dec. 3, 2021**

(30) **Foreign Application Priority Data**

May 21, 2021 (KR) 30-2021-0024229

(57) **CLAIM**

The ornamental design for an electronic blackboard, as shown and described.

DESCRIPTION

1. Electronic blackboard

1.1 : Perspective

1.2 : Rear perspective view

1.3 : Front

1.4 : Back

1.5 : Left

1.6 : Right

1.7 : Top

1.8 : Bottom

1.9 : Alternate configuration

1.10 : Another alternate configuration

The broken lines indicate portions of the electronic blackboard that form no part of the claimed design; reproductions 1.9 and 1.10 show the display part of the design in an alternate position.

1 Claim, 10 Drawing Sheets
